MILK BOTTLE CONTAINER

Lloyd N. Richardson, Lansing, Mich.

Application January 4, 1937, Serial No. 119,015

3 Claims. (CL 232—41)

This invention relates to milk bottle containers, and has for its object the provision of certain parts of special construction and arrangement whereby milk bottles and money placed with them in the container may be securely locked against removal by any one not familiar with the mechanism, or provided with a milk bottle in addition to those in the container. While the invention is in no way limited thereto, this application discloses a container fashioned to receive a series of three milk bottles arranged side by side, and the following description is in accordance therewith.

In the accompanying drawings Fig. 1 represents a top view of three bottles in the container.

Fig. 2 is a front vertical section on the line 2—2 of Fig. 1.

Fig. 3 is a vertical sectional view on the line 3—3 of Fig. 2, showing the locking bar disengaged.

Fig. 4 is a vertical section similar to Fig. 3 showing the locking bar engaged with the teeth of one sliding member.

Fig. 5 is a sectional view on a double scale of drawing showing the locking bars relating to the middle bottle. In this view are also illustrated one form of crank wires or rods for engaging and releasing the locking bars, together with the spring for drawing the lower ends of the crank wires towards each other, and further setting out the springs for elevating the locking bars when the bottle is removed.

Throughout the drawings and description, the same number is used to refer to the same part.

Considering the drawings, a container 1 of suitable form, is provided with side guide rods 2 and 3 for sliding lock members 4 and 5. There may be also provided an auxiliary guide rod 2'. The sliding members are provided upon their under surfaces with toothed angle pieces. The pieces 6 and 7 are borne by member 4, and the like pieces 8 and 9 by the member 5. The sliding member 4 has opposite semi-circular recesses 10 and 11 adapted to engage the necks of milk bottles, and the member 5 is provided with like recesses 12 and 13. The three milk bottles in the container are 14, 15 and 16.

The container is provided interiorly with vertical guide frames or partitions 17 and 18, which are supported by cross pieces 19 and 20 extending from side to side of the container. Adjacent to bottle 14, and guided in the partition or frame 17 is a vertically movable locking bar 21, provided with a curved foot or lower end 22 upon which the bottle may be placed. The middle bottle 15 has

at one side a similar locking bar 23 having the curved foot 24, and on the other side the middle bottle has a second locking bar 25 also formed with a curved lower end or foot 26. The third bottle 16 has the locking bar 27 with its curved foot piece 28 upon which the bottle may be placed.

At the sides of the bottles, as best shown in Fig. 2, are what may be termed crank wires or rods such as 29, 30 and 31, pivotally supported in the supporting partitions or walls 17 and 18. There

are also crank wires on the other sides of the bottles such as the parts 32 and 33, best shown in Fig. 5, and on the wire 33 is shown a catch block 34 engaging a lug 35 on the locking bar 25. Thus,

the only way of separating the crank wires together is by the introduction of a milk bottle. The ordinary uninformed person would not be aware of any means of operating the crank wires.

The construction illustrated in Fig. 5 shows one manner of holding the locking bars in elevated positions, from which they may be lowered by the introduction of a milk bottle placed upon the feet of the locking bars. There is also a catch block 36 on the crank wire 30 which engages a lug 37 on the locking bar 23.

There is also a sliding plate or strip 39 with an up-turned end 38 which engages a lug on the locking bar 25.

It will be understood from Figs. 3, 4 and 5, that when the bottle is introduced as in Fig. 3, the catch blocks 34 and 36 as well as the catch end 38 will be withdrawn from engagement with the lugs 35, 37, and 39' of the locking bars.

When, however, the milk bottle has been removed, the mere downward pressure on or between the locking bars will be resisted. The only way to disengage the locking bars is to separate the crank wires at the same time by the introduction of the body of a milk bottle.

In Fig. 5 is shown a coil spring 40 which acts to draw the lower ends of the crank wires 30 and 33 towards each other, from which positions they may be moved outwardly when a bottle is introduced between the wires.

Also in Fig. 5 may be noted coil springs 41 and 42, which act to elevate the locking bars 25 and 23.

In the operation of this invention, let it be assumed that the three bottles are in position as shown, and the sliding members are moved to engage the necks of bottles 14 and 16. Now, if the middle bottle 15 be removed, the locking bars 50

adjacent thereto engage the teeth of the sliding members and bottles 14 and 16 are locked. If bottle 15, or a like bottle, be again introduced the locking bars are lowered and the bottles 14 and 16 may be removed upon moving the sliding

members from the necks thereof. If bottle 16 alone is to be locked, the sliding member is moved to engage the neck, and the middle bottle is removed. If the middle bottle is to be locked, the 5 sliding member is moved to engage its neck, and bottle 16 removed. Then, the locking bar adjacent to bottle 16 will engage the teeth of the sliding member and lock the middle bottle. In other words, to free either bottle, and gain access to the 10 interior of the container, a bottle must be introduced to free the locking bars from the sliding members. The invention as illustrated is particularly useful to a customer taking two quarts of milk daily.

15 Having now described this invention and its operation, I claim:—

1. In a milk bottle container constructed to receive a series of three bottles, sliding members movable in two directions and having opposite recesses adapted to engage necks of milk bottles in the container, locking devices arranged adjacent to each bottle and adapted to be lowered by the introduction of the bottle, spring actuated means for elevating said devices, said sliding members and said devices being constructed to be engaged when a bottle is removed and disengaged when the bottle is introduced, the middle bottle having two sets of said locking devices whereby when the middle bottle is removed the remaining bottles and sliding members are locked, and are unlocked when said middle bottle is introduced.

2. In a milk bottle container constructed to re-

ceive a series of three bottles, sliding members movable in two directions and having downwardly projecting teeth and opposite recesses adapted to engage the necks of milk bottles placed in the container, locking bars arranged adjacent to each bottle and adapted to be lowered by the introduction of the bottle, spring actuated means for elevating said bars, the teeth of said sliding members and said bars being constructed to be engaged when a bottle is removed and disengaged 10 when the bottle is introduced, the middle bottle having adjacent thereto two sets of said locking bars whereby when the middle bottle is removed the remaining bottles and sliding members are locked, and are unlocked when said middle bottle 15 is introduced.

3. In a milk bottle container constructed to receive a series of three milk bottles, sliding members movable in two directions and adapted to engage the necks of milk bottles, vertically reciprocating locking bars, springs for raising the bars, said members and bars being constructed and arranged to engage and disengage by the movements of the bars, means located near the bottom 20 and within the container for engaging and securing the bars in upper positions in releasable relation and for resisting downward pressure on said bars, said means being constructed to be actuated to release the bars by the introduction between them of the body of a milk bottle.

LLOYD N. RICHARDSON.
